US00D869044S

(12) **United States Design Patent** (10) **Patent No.:** **US D869,044 S**
(45) **Date of Patent:** **** Dec. 3, 2019**

(54) **LIGHT FIXTURE**

(71) Applicant: **Hubbell Incorporated**, Shelton, CT (US)

(72) Inventors: **Armin Ahrari**, Glendale, CA (US); **Robert Nankil**, Buena Park, CA (US)

(73) Assignee: **Hubbell Incorporated**, Shelton, CT (US)

(**) Term: **15 Years**

(21) Appl. No.: **29/650,058**

(22) Filed: **Jun. 4, 2018**

Related U.S. Application Data

(63) Continuation of application No. 29/564,385, filed on May 12, 2016, now Pat. No. Des. 822,254, which is a continuation of application No. 14/689,423, filed on Apr. 17, 2015, now Pat. No. 10,215,376.

(57) **CLAIM**

We claim the ornamental design for a light fixture, as shown and described.

DESCRIPTION

FIG. 1 is a perspective view of a light fixture according our new design.

FIG. 2 is a perspective view of the light fixture shown in FIG. 1.

FIG. 3 is a perspective view of the light fixture shown in FIG. 1.

FIG. 4 is a first side view of the light fixture shown in FIG. 1.

FIG. 5 is a second side view of the light fixture shown in FIG. 1.

FIG. 6 is a first plan view of the light fixture shown in FIG. 1.

FIG. 7 is a second plan view of the light fixture shown in FIG. 1; and,

FIG. 8 is an end view of the light fixture shown in FIG. 1. The broken lines shown in the drawings illustrate portions of the light fixture and/or environment that form no part of the claimed design.

1 Claim, 4 Drawing Sheets
